UNITED STATES PATENT OFFICE.

ADOLPH C. RECKER, OF OAKVILLE, CONNECTICUT, ASSIGNOR TO WATERBURY MFG. CO.,
OF WATERBURY, CONNECTICUT, A CORPORATION.

COMBINED SHADE-HOLDER AND SOCKET-COVER.

1,287,434.

Specification of Letters Patent. Patented Dec. 10, 1918.

Application filed May 16, 1918. Serial No. 234,871.

To all whom it may concern:

Be it known that I, ADOLPH C. RECKER, a citizen of the United States, residing at Oakville, in the county of Litchfield and State of Connecticut, have invented a new and useful Improvement in Combined Shade-Holders and Socket-Covers; and I do hereby declare the following, when taken in connection with the accompanying drawings and the characters of reference marked thereon, to be a full, clear, and exact description of the same, and which said drawings constitute part of this application, and represent, in—

Figure 1 a view partly in side elevation and partly in vertical section, of a combined shade-holder and socket-cover constructed in accordance with my invention and applied to a common form of lamp-socket.

Fig. 2 a reverse plan view thereof.

Fig. 3 a sectional view of the combined shade-holder and socket-cover detached.

Fig. 4 a view partly in side elevation and partly in section, showing my improved shade-holder and socket-cover applied to another form of socket.

My invention relates to an improved combined shade-holder and socket-cover for use in conjunction with standard incandescent electric lamp-sockets, the object being to produce a simple and convenient shade-holder performing the supplemental function of partly inclosing the lamp-socket and so improving the appearance of the fixture but without making any change in the wiring necessary as is the case when the shade-holder is made to entirely inclose and cover the lamp-socket.

With these ends in view, my invention consists in a combined shade-holder and socket-cover having certain details of construction as will be hereinafter described and pointed out in the claim.

In carrying out my invention as herein shown, I employ a bell-shaped shell consisting of a tapering body 2 from which an integral shade-receiving flange 3 depends, the said flange substantially corresponding in depth to an ordinary shade-holder and mounting a plurality of thumb screws 4 the projecting inner ends of which are engaged with the flange or lip at the upper end of the shade. Within the said body I locate a concentrically arranged sleeve 5 the lower end of which is formed

with threads 6 and the upper end of which is shaped to form a groove 7 for the reception of the inwardly turned upper edge of the said body, whereby the sleeve is mounted therein.

When such a combined shade-holder and socket-cover is applied to an ordinary incandescent lamp-socket 9, the threads 6 of the sleeve 5 are screwed upon the threads 10 near the lamp-receiving end of the socket 65 until the upper edge of my improved combined part is brought to a bearing upon the shoulder 11 of the socket, as shown in Fig. 1, the said shoulder forming a seat for the combined holder and cover to be screwed 70 against. The lines of the combined part now merge into the lines of the upper portion of the socket and form an attractive design, concealing the awkward contracted lower end of the socket. I thus provide 75 a combined socket-cover and shade-holder which avoids the covering of the entire socket with its attendant objections in the way of wiring.

In the application of my invention shown 80 by Fig. 4, my improved combined part is applied to a lamp-socket 12 having threads 13 formed at its extreme lower end and flanked on the inside by an independently 85 formed bead 14. When my improved combined device is applied to a socket of this form, the threads 6 of the sleeve 5 engage with the threads 13, but the bead 14 forms an abutment which prevents the upper edge 90 of the combined part from being seated 95 against the shoulder 11 of the socket. The effect of the construction shown by Fig. 4 is substantially the same as that shown by Fig. 1, and the same advantages are secured of improving the exterior appearance 95 of the socket by partially covering it, without changing the mode of wiring it.

It will be noted that the depth of the body 2 is so proportioned to the length of the sleeve 5 that the body extends sufficiently 100 below the lower end of the sleeve to entirely conceal the awkward contracted lower end of the socket 12 which is highly desirable, as already explained. In such construction the lower end of the sleeve stops well above 105 the horizontal plane of the thumb-screws 4 so that ample space is provided for the reception of the flange or lip of the shade.

I claim:

A combined shade-holder and lamp-socket 110

- cover for incandescent lamp-sockets consisting of a bell-shaped shade-carrying body furnished at its lower end with shade-retaining means, and an independently formed 5 concentric socket-coupling sleeve located within the upper portion of the said body and having its upper end connected with the upper end thereof and its lower end threaded for engagement with the threads 10 at the lower end of the threaded and shouldered lamp-socket upon which the said structure is positioned by the engagement of its upper end with the shoulder thereof, the said body and sleeve being proportioned in 15 length so that the body extends sufficiently

below the lower end of the sleeve to conceal the contracted lower end of the socket and the lower end of the sleeve stopping above the horizontal plane of the shade-retaining means mounted in the lower end of the body 20 for engagement with the lip or flange of the shade.

In testimony whereof, I have signed this specification in the presence of two subscribing witnesses.

ADOLPH C. RECKER.
